(57) **CLAIM**

I claim the ornamental design for a drying rack for baby bottles and other items, as shown and described.

DESCRIPTION

FIG. 1 is a perspective view of a drying rack for baby bottles and other items, showing my new design;

FIG. 2 is a front elevational view thereof;

FIG. 3 is a rear elevational view thereof;

FIG. 4 is a left end elevational view thereof;

FIG. 5 is a right end elevational view thereof;

FIG. 6 is a top plan view thereof;

FIG. 7 is a bottom plan view thereof;

FIG. 8 is a perspective view of thereof in a folded condition; and,

FIG. 9 is a perspective view thereof in use, the dashed lines illustrating environmental structure that forms no part of the design.

1 Claim, 6 Drawing Sheets
